UNITED STATES PATENT OFFICE.

WILLIAM DIETER, OF NEWARK, NEW JERSEY, ASSIGNOR TO E. W. BLISS COMPANY, OF BROOKLYN, NEW YORK, A CORPORATION OF DELAWARE.

STOP VALVE FOR TORPEDOES.

Application filed August 25, 1925. Serial No. 52,383.

This invention relates to automobile torpedoes of which the Bliss-Leavitt torpedo, the standard of the United States Navy, is an example, in which compressed air from a flask or reservoir is passed at reduced pressure through a heater in which a combustible such as alcohol is burned, and into which water is sprayed, and the resulting mixture of combustion gases and steam is discharged to drive a turbine or other motor by which the torpedo is propelled.

The present invention relates to means for shutting off the water and fuel tanks when the torpedo is not in use and for putting them in communication with the respective passages upon the starting of the torpedo on its run. For this purpose stop valves are commonly used, an example of which is contained in the patent to F. M. Leavitt, No. 1,022,486, dated April 9, 1912, in which upon the opening of the starting valve air from the low pressure or working pressure side of the reducing valve is conducted to stop valves leading to the tops of the respective tanks, its pressure serving to open these valves and the pressure thus applied over the liquids in the two tanks serving to open the outlet valves in the passages leading from these tanks respectively to the heater. Stop valves of the construction shown in said patent have been found generally acceptable, but have been subject to certain minor defects or disadvantages which it is the object of the present invention to overcome.

According to the present invention the respective stop valves are operated by high pressure air instead of low pressure air. These terms are well understood in the torpedo art. The air at high or flask pressure is usually at an initial pressure of at least 3000 pounds per square inch, which pressure falls progressively during the run of the torpedo; while air at low or working pressure is usually between 400 and 500 pounds per square inch. By utilizing the high pressure air the stop valves are opened instantaneously and with absolute certainty and the closed condition of the valves is rendered far more reliable than heretofore, because springs of much greater strength can be used than was possible when they were opened by low pressure air. The low pressure air is admitted as heretofore upon the opening of the upper stop valves to enter the tops of the two tanks, but the pressure

of this air has no effect in opening the valves, this being done by the high pressure air. Thus instead of connecting the low pressure air merely to the upper stop valves the high pressure air is connected to both upper and lower valves and the low pressure air connection to the upper valves is so modified that the low pressure air may pass upon the opening of these valves to the tops of the liquid tanks.

The preferred embodiment of the present invention is shown in the accompanying drawings wherein,—

Figure 1 is a fragmentary vertical mid-section of the mid portion of a torpedo, the valves and heater being arranged schematically to make their connections clear.

Fig. 2 is a vertical mid section of the lower stop valves.

Fig. 3 is a similar section of the upper half of the upper stop valves (the lower half thereof being the same as shown in Fig. 2).

Fig. 4 is a similar section, showing a modified construction of either the upper or lower valves.

Referring first to Fig. 1, A is the shell or hull of the torpedo, B is the compressed air flask, C is the valve group and D is the heater (commonly called the superheater). From the flask B there extends as usual a conduit conducting compressed air to the heater and thence to the engine or turbine; this includes a high pressure air pipe *a* leading into the starting valve member *b* of the valve group C; when the starting valve is opened the air passes into the pressure reducer *d* forming part of the valve group and from the low pressure side thereof a conduit *e* leads the air at working pressure to the heater D from which a conduit *f* leads to the turbine or other motor. The starting valve and reducer may be as shown in my Patent No. 1,211,104. E designates the upper pair of stop valves and F the lower pair. From the low pressure conduit *e* a duct *g* leads low pressure air to the stop valves E, and when these valves are opened the low pressure air is conveyed through ducts or tubes *h* *i* to the upper parts of the respective liquid tanks. These tanks are shown as of the customary construction, the water tank H being formed within a prolongation of the pressure flask shell enclosed by a head *j* and the alcohol tank I being mounted concentrically within it. The tubes *h* *i* open into the up-

per parts of these tanks; from the lower parts of the tanks lead outflow ducts or tubes *k* and *l* respectively which connect with the pair of stop valves *F* and continuations of these pipes lettered *l'* and *k'* extend to the heater *D* and terminate the one in the fuel spray nozzle and the other in the water spray nozzle, as usual.

So far as described the construction and arrangement are the same as heretofore except for the internal construction of the valves *E* and *F* which will now be described.

Referring to Fig. 2, which shows the lower pair of stop valves *F*, each of these comprises a suitable shell or casing *m* within which is a valve seat *n* and against this seats a tappet or check valve *p* closing off communication between the inlet opening *t* and the outlet opening *l'* of the left-hand valve or similarly the inlet opening *k* and outlet opening *k'* of the right hand valve. The check valves *p* close with the flow and are pressed down by suitably stiff springs *q* so as to afford a certain and reliable closure which in the inactive condition of the torpedo will effectually prevent any escape of liquid from either tank to the heater. Each valve *p* has a stem *p'* projecting down into a chamber or cylinder *r* in which operates a plunger *s* which normally is held down in the position shown. This position of the plunger is assured by the stress of the spring *g* transmitted through the pin *p'*. At *t* is an inlet for high pressure air, the connection being made through the tube *t* shown in Fig. 1 which connects with the valve group on the high pressure side of the reducer *d*. When the starting valve is opened, this high pressure air passes through *t* into an air chamber or passage *t'* in the valve casing and acts beneath both plungers *s*, forcibly lifting them and thereby unseating the valves *p*, *p'* and establishing communication through the channels *t*, *t'* and *k*, *k'* for the outflow of liquid from the tanks to the heater. Owing to the extremely high pressure of the air the plungers *s*, *s* are thrown up with a great force and it is desirable to provide cushioning washers *u* between their enlarged heads and annular stops formed in the casing.

The upper valves *E* are of like construction at the bottom and of similar construction at the top, as shown in Fig. 3, having the same valve seats *n* and check valves *p* and springs *q*; but the connections on opposite sides of the valve seats are somewhat different. On the right hand in Fig. 3 is the inlet connection for the low pressure air pipe *g* and the outlet connection for the low pressure air pipe *h*. On the left is the outlet connection for the pipe *i*. To convey low pressure air to the left-hand valve the simplest way is to form an interior passage *g'* as shown. High pressure air is conveyed to the upper valve by a duct *v* branching from

the duct *t* or otherwise directly from the high pressure side of the reducer.

It results from the construction thus described that while the torpedo is in storage and before launching the four stop valves 70 are held closed by their check valves *p*, being pressed to their seats very firmly by the springs *q* which may be very strong or stiff so that there is no possibility of leakage from the tanks *H* and *I* either through the 75 lower or upper valve; so that in this respect the stop valves operate with much greater certainty and positiveness than those heretofore used. Upon the launching of the torpedo the starting valve *b* being opened in the usual way by the operation of the launching trigger (which vents pressure from above the plunger of this valve through a vent duct *w* as is well understood, the means used in practice being that shown in my Patent No. 1,303,045) high pressure air is at once admitted to the ducts *t* and *v* and thence beneath the plungers *s*, *s* of the respective stop valves, thereby forcibly lifting these plungers, and unseating the check valves *p* and thereby establishing full communication through the respective stop valves. This operation being performed by air at high pressure is instantaneous and is of absolute certainty. Thereupon low pressure air enters through *g* and passing through the upper stop valves flows through *h* and *i* into the tops of the tanks *H* and *I*, and exerts a pressure upon the liquids therein, (by means shown in my said Patent No. 1,211,104) 100 tending to force these liquids out, and the liquid flow takes place through the ducts *l*, *l'* leading alcohol to the heater and through the ducts *k* and *k'* leading water to the heater.

Upon the automatic stoppage of the torpedo which as is well understood closes again the starting valve *b* the high pressure air quickly escapes through the reducer and out to the turbine so that the pressure in *t* and *v* drops and the respective check valves *p*, *p'* are replaced by their springs so as to close all communication with the two liquid tanks.

While the construction just described is considered the preferable embodiment of the 115 invention, yet it is to be understood that the same is subject to considerable variation. While the check valves of the tappet type are preferable, yet other types of stop valves may be used. The high pressure air may act directly or indirectly to open these valves. An example of one suitable modification is shown in Fig. 4, where the construction is the same as in the upper half of Fig. 2, the valves *p* and their stems *p'* and springs *q* being unchanged; but instead of the plungers *s*, *s* in Fig. 2 a single horizontally moving plunger *x* is provided which is forced to the left by the high pressure air; in its upper side are notches *y*, *y* 125

which are entered by the valve stems and which have inclined sides so that as the plunger moves to the left these act as wedges to lift the valve stems. A spring x' restores the plunger x when the air pressure escapes.

To insure the operation of the plungers s and x and provide against trapping of air or fluid beyond them, it is preferable to provide minute vent openings z , as shown 10 in Figs. 2 and 4.

It will be understood that while I have illustrated my invention as applied to a torpedo having two liquid tanks H and I yet it is equally applicable to torpedoes having 15 only a single tank. Also while preferably both the upper and lower stop valves are operated by high pressure air according to my present invention yet it is possible to only partially avail of my invention by operating only one set of valves in this manner.

When the vent openings z are used it will be desirable to connect them to the after-body by tubes z' z'' as shown in Fig. 1, in order to isolate these vents from the mid-chamber and prevent the possibility of water 25 entering into the plunger chambers r of the stop valves.

I claim as my invention:

1. In an automobile torpedo having a 30 compressed air flask, a heater, a conduit leading from the flask to said heater, a pressure reducer in said conduit, a liquid tank having a compressed air duct leading from the low-pressure side of said reducer to the upper part of said tank and a liquid duct leading from the lower part of said tank to the heater, and a stop-valve controlling at least one of said ducts, the combination 35 therewith of means for admitting air from the high pressure side of said reducer to operate said stop-valve.

2. In an automobile torpedo having a compressed air flask, a heater, a conduit leading from the flask to said heater, a pressure 40 reducer in said conduit, a liquid tank having a compressed air duct leading from the low-pressure side of said reducer to the upper

part of said tank and a liquid duct leading from the lower part of said tank to the heater, and stop-valves controlling said ducts 50 respectively, the combination therewith of means for admitting air from the high pressure side of said reducer to operate said stop-valves.

3. In an automobile torpedo having a 55 compressed air flask, a heater, a conduit leading from the flask to said heater, a pressure reducer in said conduit, liquid and fuel tanks, compressed air ducts leading from the low-pressure side of said reducer to the 60 upper part of said tanks respectively, and liquid ducts leading from the lower parts of said tanks to the heater, and stop-valves controlling at least one of said ducts for each tank, the combination therewith of means 65 for admitting air from the high-pressure side of said reducer to operate said stop-valves.

4. In an automobile torpedo having a 70 compressed air flask, a heater, a conduit leading from the flask to said heater, a pressure reducer in said conduit, a liquid tank having a compressed air duct leading from the low-pressure side of said reducer to the upper part of said tank and a liquid 75 duct leading from the lower part of said tank to the heater, and a stop-valve controlling at least one of said ducts and normally closing communication therethrough, the combination therewith of means for admitting 80 air from the high pressure side of said reducer to operate said stop-valve, whereby to open communication through said duct.

5. In an automobile torpedo, according to 85 claim 1, the stop-valve having a spring-seated check valve for closing communication through said duct, and a plunger connected to open said check valve, combined with means for admitting air from the high pressure side of said reducer to operate said 90 plunger and thereby open said check valve.

In witness whereof, I have hereunto signed my name.

WILLIAM DIETER.
